[57] CLAIM

The ornamental design for an optical disc cartridge, as shown and described.

DESCRIPTION

FIG. 1 is a top plan view showing our new design;
 FIG. 2 is a left-side view thereof;
 FIG. 3 is a front view thereof;
 FIG. 4 is a right-side view thereof;
 FIG. 5 is a backview thereof;
 FIG. 6 is a bottom view thereof;
 FIG. 7 is a front view in its open position thereof;
 FIG. 8 is a perspective view thereof; and,
 FIG. 9 is a backview thereof my design being shown in its open position.
